UNITED STATES PATENT OFFICE

169,793

LIQUID DISPENSER

Edward H. Sieling, Chicago, Ill.

Application July 31, 1952, Serial No. 20,860

Term of patent 14 years

(Cl. D2—3)

To all whom it may concern:

Be it known that I, Edward H. Sieling, a citizen of the United States, residing at Chicago, in the county of Cook and State of Illinois, have invented a new, original, and ornamental Design for a Liquid Dispenser, of which the following is a specification, reference being had to the accompanying drawing, forming a part thereof.

In the drawing:

Fig. 1 is a perspective view of a liquid dispenser embodying a new design; and

Fig. 2 is a top plan view of the dispenser illustrated in Fig. 1.

The opposite side to that shown in Fig. 1 is substantially the same.

I claim:

The ornamental design for a liquid dispenser, as shown and described.

EDWARD H. SIELING.
